(57) **CLAIM**

The ornamental design for a cosmetic brush cleaning machine, as shown and described.

DESCRIPTION

FIG. 1 is a front perspective view of a cosmetic brush cleaning machine, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and

FIG. 9 is an enlarged detail view of area 9 in FIG. 1 thereof; and,

FIG. 10 is an enlarged detail view of area 10 in FIG. 2. The broken lines in the drawings illustrate the portions of the cosmetic brush cleaning machine, which form no part of the claimed design.

The dash-dot-dash broken lines in the drawings indicate cutoff boundaries for the enlarged detailed portion views and form no part of the claim thereof.
